United States Patent Office

Des. 217,143
Patented Apr. 14, 1970

217,143

MOTOR HOME

Robert E. Bourke, Weston, Conn., assignor to Superior
Coach Corporation, Lima, Ohio, a corporation of Ohio

Filed June 2, 1969, Ser. No. 17,471

Term of patent 14 years

Int. Cl. D12—08

U.S. Cl. D14—3

FIG. 2

FIG. 1 is a front perspective view showing a motor home embodying my design; and

FIG. 2 is a rear perspective view of the motor home shown in FIG. 1 and further showing the side of the motor home opposed to the side shown in FIG. 1.

I claim:

The ornamental design for a motor home, as shown.
